GUN SILENCER AND SCAVENGER

John L. Brown, Momence, Ill.

Application July 12, 1939, Serial No. 284,098

15 Claims. (Cl. 89—14)

The invention aims to provide a new and improved gun silencer equipped with scavenging means whereby compressed air or other scavenging fluid may be used after each projectile has passed through the silencer, to drive out remaining gases, smoke and flame and prevent them from interfering with the accuracy of the next shot.

A further object is to provide for driving the gases, smoke and flame downwardly so that the latter will be not as clearly visible at night, particularly to observers and others in reconnoitering aircraft.

The present disclosure of the invention is particularly adapted for use with various kinds of 15 m. m. guns, mountain guns, anti-tank guns and small naval guns, but it will be understood to those skilled in the art that the invention is adaptable also to guns of other caliber and of other varieties.

With the foregoing in view, the invention resides in the novel subject matter hereinafter described and claimed, description being accomplished by reference to the accompanying drawings.

Figure 1 is a perspective view with the removable side plate removed.

Figure 2 is a horizontal section on line 2—2 of Fig. 1.

Figure 3 is a transverse section on line 3—3 of Figure 1 showing the scavenging valves open.

Figure 4 is a transverse section on line 4—4 of Fig. 1 showing the valves closed.

Figure 5 is a perspective view.

Figure 6 is a perspective view of the baffle assembly removed from the casing.

Figure 7 is a disassembled perspective view of the upper valve.

Figure 8 is a similar view of the lower valve.

Figure 9 is substantially a central vertical 40 longitudinal section partly broken away.

A preferred construction has been illustrated and will be rather specifically described, with the understanding, however, that within the scope of the invention as claimed, variations may be made.

An elongated casing 15 is shown, the top 16, bottom 17 and one vertical side 18 of said casing being preferably formed integrally with each other. The front plate 19, rear plate 20 and the second side wall 21, however, are preferably detachably secured in place. Screws 22 are shown for securing the front and rear plates 19 and 20 in place, said screws being threaded into suitable flanges 23 on the side wall 18, the top 16 and the bottom 17. Bolts 24 have been shown for securing the removable side wall 21 in place, said bolts passing through longitudinal flanges 25 formed on the top and bottom 16 and 17, respectively. The rear plate 20 carries a rigid nip-

ple 26 to be threaded onto the muzzle of the gun barrel, said nipple and end plate being relatively braced by suitable webs 27.

Within the rear portion of the casing 15, a set of relatively small baffles 28 is provided having their edges spaced from the top, bottom and side walls of said casing. In the intermediate portion of the casing, I provide another set of baffles 29 which are disposed relatively far apart. In the front portion of the casing, I also provide a third set or series of baffles which are disposed in relatively close relation. The edges of all of the baffles 29 and 30 are preferably in substantial contact with the top, bottom and side walls of the casing and all of these baffles 15 are rigidly tied together, for instance, by a longitudinal tie rod 31 passing through the upper ends of said baffles, and nuts 32 on said rod and abutting said baffles. One of the baffles 30 and one of the baffles 29 are preferably provided each 20 with a flange 33 into which screws 34 are threaded, said screws securing the baffles to the removable side wall 21. The relatively small baffles 28 are preferably welded or otherwise secured to a pair of rearwardly projecting plates 25 35 which are in turn welded or otherwise secured to the rearmost of the baffles 29. Interposed between the lower portions of the front baffles 30 and the intermediate baffles 29, are transversely inclined plates 36 which are welded 30 or otherwise secured to said baffles and perform a function hereinafter described. Two similar plates 36' are disposed under the small baffles 28 and are secured to the latter and to the rearmost of the baffles 29.

The various baffles 28, 29 and 30 are unitarily connected by means of the arms 35, tie rod 31 and downwardly converging plates 36 and 36', and this entire unit may be bodily removed from the casing 15 for repair, when the side wall 21 is removed. When reinserting the baffle unit, it is held in place solidly against the rear wall or plate 20, by means of the screws 34. The baffle unit is necessarily somewhat shorter than the casing in order that it may pass between the flanges 23 of the front and rear end plates 19 and 20, but after insertion, the baffle unit is slipped rearwardly into abutting contact with the rear plate 20, in which position, it is held when the slide plate 21 and its fasteners are in place. All of the baffles are of course provided with 45 aligned openings 37 through which the projectile travels.

Compressed air inlets 38 are formed through the casing top 16 between the baffles 29 and between the baffles 30; another compressed air inlet 38' is formed through said top over the small baffles 28. Immediately behind this inlet 38', are one or more forwardly declined nipples 39 which are also intended to admit compressed air. 50 55 60

The casing bottom 17 is formed with discharge slots 40 for the compressed air, smoke, flame and gases, and the plates 36 and 36' downwardly converge to these discharge slots from the sides 5 18 and 21 of the casing to guide the compressed air, smoke, etc. downwardly to said slots. One valve assembly 41 is mounted upon the casing top 16 and is provided with a compressed air inlet 42 for connection with a hose or the like 43 leading 10 from a suitable source of compressed air. The valve assembly 41 includes a rotatable valve member 41' which cuts off communication between the inlet 42 and the air admission ports 38, 38' and 39 until the projectile has left the silencer, 15 and is then intended to establish the necessary communication to cause forcible downward blast of compressed air to be directed across the casing between the baffles, driving out the products of combustion through the discharge slots 40. Another valve assembly 43 extends longitudinally 20 of the casing bottom 17 and includes a rotatable valve member 44 which is intended to prevent communication between the discharge slots 40 and the atmosphere until after the projectile has 25 left the silencer, and is intended to then establish said communication. In order that the upper and lower valve members 41' and 44 shall move simultaneously from closed to open position and vice versa, I provide the rear ends of said valves 30 with crank arms 42' and 44' respectively, and connect said crank arms by a vertical link 45. The arm 42' is extended beyond the link and provided with a suitable handle 46. When this handle is in raised position as seen in Fig. 4, the 35 fluid admission and discharge ports are all closed and the valves remain in these positions until the projectile has passed through the silencer. Then, the handle 46 is forced downwardly to the 40 position shown in Fig. 3, thus simultaneously effecting opening of both the upper and the lower valves, with the result that compressed air is forcibly directed downwardly across the interior of the casing and out through the discharge slots, carrying with it all products of combustion which 45 would otherwise accumulate and interfere with accurate flight of the next projectile. The nozzles 39 in addition to assisting in downwardly discharging the products of combustion, direct oblique jets of compressed air across the front 50 end of the nipple 36 which forms a continuation of the gun muzzle, and said nipple thus effects an aspirating action upon remaining gases in the gun barrel. The rear baffles 28 perform the initial breaking up of the gas and smoke plume as it leaves the gun barrel, more breaking up is effected by the baffles 29, and the final breaking up 55 is done by the baffles 30. All smoke, gases and flame mix with the compressed air downwardly discharged across the interior of the casing, and escape with it to the atmosphere. The discharge 60 valve being at the bottom, flame will not be as visible at night, as otherwise, particularly to pilots and others flying overhead.

The air admission valve assembly 41 preferably includes a tubular casing 47 for the valve 41', the latter being also tubular, said casing 47 having peripheral grooves 48 in which clamp members 49 are received, said clamp members being secured to the casing top 16, the casing 47 being thus held against endwise and other movements. The bottom 50 of the casing 47 is preferably flat for contact with the casing top 16, and said bottom is provided with appropriate 65 ports 51, 51' and 52 for registration with the admission slots 38, 38' and the nozzles 39 respec-

tively. The tubular valve 41' is provided at its rear end with the compressed air inlet 42 and at this same end with the arm 42'. This arm abuts the rear end of the casing 47, and a nut 53 is threaded on the front end of the valve to abut 5 the front end of said casing, rotatably mounting the valve for holding it against other movement. This valve is provided with suitable ports 54, 54' and 55 for coaction with the ports 51, 51' and 52 of the casing 47. The valve 41' is, of course, 10 inserted into the casing 47 from the rear and the nut 53 is then applied.

The emission or discharge valve assembly 43 includes a tubular casing 56 mounted in the same manner as the casing 47, the upper flattened side 15 of said casing 56 being provided with ports 57 communicating with the discharge slots 40. The lower side of the casing 56 is provided with similar ports 58. The rotary valve member 44 which is received in the casing 56 is provided in its upper and lower sides with ports 59 and 60 for communication with the ports 57 and 58 respectively. When the valve 44 is inserted into the casing 56 from the rear, its arm 44' abuts the front end of said casing. A nut 61 is then 25 threaded upon the front end of the valve to abut the front end of said casing.

As to operation, with both the upper and lower valves 41' and 44 closed, the gun is fired. The handle 46 is then pushed downwardly to open 30 both valves, whereupon downward blasts of compressed air (or other scavenging fluid) are directed across the casing between the baffles and obliquely forward from the nozzles 39, driving out all products of combustion as these products 35 are broken up by the baffles and mixed with the compressed air or the like. By thus effectively scavenging the silencer after each shot, no accumulated gases remain to interfere with accurate flight of the next projectile. Moreover, an 40 effective cooling operation is performed, not only on the silencer itself but upon the gun barrel, as the aspirating effect of the nozzles 39, drawing out products of combustion from the barrel, tends to keep the latter somewhat cooler.

As excellent results may be obtained from the general construction shown and described, it is 45 preferably followed. However, within the scope of the invention as claimed, variations may of course be made.

What is claimed is:

1. In combination with a gun silencer; means for admitting a scavenging fluid to and emitting said fluid from said silencer after gun firing, said means having fluid-controlling valve means 55 to remain closed until the projectile leaves the silencer.
2. In combination with a gun silencer having transverse baffles; means for directing a scavenging fluid across said silencer and for discharging 60 said fluid from said silencer after gun firing, said means having fluid-controlling valve means to remain closed until the projectile leaves the silencer.

3. In combination with a gun silencer having a 65 casing and transverse baffles therein; admission means for admitting a scavenging fluid to said casing between said baffles, said fluid admission means having a fluid-controlling valve to remain closed during gun firing, and means for discharging the scavenging fluid from said casing, said fluid discharge means also having a fluid-controlling valve to remain closed during gun firing.

4. A structure as specified in claim 1; said valve means comprising an admission valve and 75

an emission valve, and means connecting said valves for movement simultaneously from closed to open position and vice versa.

5. A structure as specified in claim 3; together with means connecting said valves for movement simultaneously from closed to open position and vice versa.

6. A combined gun silencer and scavenger comprising a casing having transverse baffles, the top of said casing being provided with admission ports between said baffles for admitting a scavenging fluid to the casing after gun firing, the bottom of said casing being provided with fluid discharge ports between said baffles, and a valve assembly mounted on said casing top and having an inlet for the scavenging fluid, said assembly having a rotatable valve for either permitting flow of the fluid from said inlet to said admission ports or for preventing said fluid flow according to the position to which said valve is turned.

7. A combined gun silencer and scavenger comprising a casing having transverse baffles, the top of said casing being provided with admission ports between said baffles for admitting a scavenging fluid to the casing after gun firing, the bottom of said casing being provided with fluid discharge ports between said baffles, a valve assembly mounted on said casing top and having an inlet for the scavenging fluid, said assembly having a rotatable valve for either permitting flow of the fluid from said inlet to said admission ports or for preventing said fluid flow according to the position to which said valve is turned, a second valve assembly mounted on the bottom of the casing and having a rotatable valve for either placing said discharge ports in communication with the atmosphere or for preventing said communication according to the position to which the valve is turned, and means connecting the two valves for simultaneous turning from closed to open position or vice versa.

8. A combined gun silencer and scavenger comprising a casing having transverse baffles, the top of said casing being provided with admission ports between said baffles for admitting a scavenging fluid to the casing after gun firing, the bottom of said casing being provided with fluid discharge ports between said baffles, inclined fluid guiding plates in said casing converging downwardly from the casing side walls to said discharge ports, and a valve assembly on said casing for conducting a scavenging fluid to said admission ports after gun firing.

55. A combined gun silencer and scavenger comprising a casing having transverse baffles, the top of said casing being provided with admission ports between said baffles for admitting a scavenging fluid to the casing after gun firing, the bottom of said casing being provided with fluid discharge ports between said baffles, inclined fluid guiding plates in said casing converging downwardly from the casing side walls to said discharge ports, a valve assembly on said casing for conducting a scavenging fluid to said admission ports after gun firing, and a second valve assembly on said casing for placing said discharge ports in communication with the atmosphere after gun firing.

70. 10. A combined gun silencer and scavenger comprising a casing, a rear set of transverse baffles in said casing, means mounting said rear set of baffles with their edges spaced from the top, bottom and side walls of

top, bottom and side walls of the casing, additional transverse baffles mounted in said casing between said rear set and the front wall of the casing, the edges of said additional baffles being substantially in contact with said top, bottom and side walls of the casing, said top being provided with scavenging fluid admission ports over said rear baffles and between said additional baffles, said bottom being provided with scavenging fluid discharge ports under said rear baffles and between said additional baffles, a valve assembly mounted on said casing and having a scavenging fluid inlet, said assembly having a valve member for either placing said fluid inlet in communication with said admission ports or for preventing said communication, and a second valve assembly mounted on said casing and having a valve member for either placing said discharge ports in communication with the atmosphere or for preventing said communication.

11. A structure as specified in claim 10; together with an inclined fluid admission means through said top over said rear baffles for downwardly and forwardly directing a blast of the scavenging fluid to aspirate gases and flame from the gun barrel, the first mentioned valve member having provision for placing said inclined fluid admission means in communication with said fluid inlet when said valve member places said admission ports in communication with said inlet.

12. A combined gun silencer and scavenger comprising a casing having baffles, means at one side of said casing for admitting a scavenging fluid after gun firing, and means at the opposite side of said casing for emitting said fluid, said fluid-admitting means including an inclined passage positioned to direct a blast of the scavenging fluid obliquely forward in the rear portion of the casing to aspirate gases and flame from the gun barrel.

13. A gun silencer comprising a casing, a rear set of transverse baffles in said casing, means mounting said rear set of baffles with their edges spaced from the top, bottom and side walls of said casing, and additional transverse baffles mounted in said casing between said rear set and the front wall of the casing, the edges of said additional baffles being substantially in contact with said top, bottom and side walls of the casing.

14. A gun silencer comprising a casing, a rear set of transverse baffles in said casing, means mounting said rear set of baffles with their edges spaced from the top, bottom and side walls of said casing, a front series of transverse baffles mounted in the front portion of said casing and disposed in relatively closely spaced relation, and an intermediate set of transverse baffles mounted in the intermediate portion of said casing and disposed in relatively widely spaced relation, the edges of said front and intermediate baffles being substantially in contact with the top, bottom and side walls of the casing.

15. A structure as specified in claim 13; said means for mounting said rear baffles being rigidly secured to one of said additional baffles, and means rigidly connecting all of said additional baffles with each other to provide a single baffle unit bodily removable from said casing, said casing having a removable side wall to permit removal of said unit.

JOHN L. BROWN.
